UNITED STATES PATENT OFFICE.

GEORGE WITTY, OF SCRANTON, PENNSYLVANIA, ASSIGNOR OF ONE-HALF TO STEPHEN S. SPRUKE, OF SCRANTON, PENNSYLVANIA.

SIGNALING SYSTEM.

1,128,210.

Specification of Letters Patent.

Patented Feb. 9, 1915.

Application filed January 10, 1913. Serial No. 741,315.

To all whom it may concern:

Be it known that I, GEORGE WITTY, a citizen of the United States of America, residing at Scranton, in the county of Lackawanna and State of Pennsylvania, have invented new and useful Improvements in Signaling Systems, of which the following is a specification.

This invention relates to improvements in signaling systems and has particular application to wireless systems wherein the transmission of the signals is accomplished by electromagnetic waves.

In carrying out the present invention, it is my purpose to provide a wireless signaling system which will be found especially useful for transmitting signals between railroad trains, trains and signal towers and between ships at sea.

It is also my purpose to provide a portable wireless signaling apparatus or outfit which may be readily positioned upon the vehicle to which it is applied and which will embody, among other features, wave transmitting and receiving sets each including an antenna or aerial, a second antenna or aerial composed of a reflector, and means whereby either of the antennae or aerials may be placed in circuit with the respective set.

With the above and other objects in view, the invention consists in the construction, combination and arrangement of parts hereafter set forth in and falling within the scope of the claims.

In the accompanying drawings;

Figure 1 is a view in front elevation of an electromagnetic wave signal apparatus constructed in accordance with my present invention. Fig. 2 is a top plan view thereof. Fig. 3 is a diagrammatic view of the apparatus. Fig. 4 is a vertical sectional view through one of the reflectors. Fig. 5 is an enlarged fragmentary elevation of one of the reflectors. Fig. 6 is a detail view of a ground plate. Fig. 7 is a view in elevation, partly in section, of the throttle controlling device. Fig. 8 is a similar view of the device for controlling the engineer's brake valve, and Fig. 9 is a diagrammatic view of the train stopping apparatus.

Referring now to the accompanying draw-

ings in detail, the numeral 1 indicates a suitable box-like structure having a hinged closure 2 whereby access may be had to the interior thereof, while the numeral 3 designates a standard uprising from the upper surface of the box-like structure and having pivotally mounted on the upper end thereof an appropriate form of telescope 4 by means of which the engineer of a train or the signalman in a signal tower, as the case may be, may ascertain the condition of the track ahead or the general conditions of the roadway. At one corner of the box-like structure is a vertical supporting rod 5 having pivotally connected thereto one end of a set of lazy tongs 6 the free end of the lazy tongs carrying a base 7 upon which is swiveled for universal movement an appropriate form of search light 8 connected in circuit with a battery or other suitable source of electrical energy 9 disposed within the box 1, a switch 10 being located in the circuit so that the search light may be cut in and out of service. A supporting lug 11 is suitably connected to one side wall of the box so as to support the free end of the lazy tongs structure when the search light is inactive. By means of the telescope and the search light, the operator using the apparatus may view the way ahead by day and by night.

Each signaling apparatus embodies electro-magnetic wave transmitting and receiving sets, as illustrated diagrammatically in Fig. 3. In the present instance, the receiving set includes some suitable form of coherer 12 having one side connected to ground as at 13 and the opposite side adapted to be placed in circuit with my improved antenna 14 or with the ordinary antenna 15 upstanding from the engine cab or other structure in which my improved signaling apparatus is installed. As usual the coherer 12 is under the influence of a tapper 16 and controls a circuit including a source of energy such for instance as a battery 17 and a form of sounder 18, the latter being adapted to be energized and operated when the metallic particles in the coherer are caused to cohere under the action of the energy passing through the coherer from the aerial to

the ground, as is well understood. In the embodiment of my invention selected for illustrative purposes, the transmitting set comprises an electric circuit including a 5 source of energy as a battery 17, an induction coil or transformer 18 having the usual vibrator 19, and a key 20 adapted to close the circuit through the primary or induction coil, the secondary of the transformer 10 being connected to a spark gap 21 having one side grounded as at 22 and the opposite side adapted to be connected to an aerial or antenna 22, a condenser 23 being connected in the primary circuit for the well 15 known purpose.

The transmission and receiving sets in addition to the respective aerials 13 and 22 each includes a supplemental or auxiliary antenna or aerial composed of a reflector 24 20 capable of receiving or transmitting as the case may be electromagnetic waves and reflecting light formed of a concave body 25 for absorbing the magnetic lines of force having the marginal edge thereof inturned 25 to form a flange 26 to hold a concave reflecting section 27. Each reflector 24 is suitably connected to the upper end of a hollow standard 28 secured to and extending upwardly from the top surface of the box 1, 30 while a conductor 29 has one terminal connected to the reflecting section 27 of the respective reflector and the opposite terminal thereof tapped onto a contact 30 disposed in the path of movement of a switch 35 blade 31. The switch blades 31 control the connections between the aerials 13 and 22 and the receiving and transmitting sets respectively and between such sets and the reflecting aerials 24. Each reflector 24 carries an electric lamp 32 disposed at the center thereof and connected in circuit with a battery 33, a switch 34 controlling communication between the battery and the lamp.

The purpose of the lamps 32 is to give a 45 beam of light that can be intermittently flashed for giving a passing station a private message.

In the present instance, the upper end of each standard 28 is secured to the respective 50 reflector by means of screws 35 threaded into apertures 36 in the shield 25, while the wire 29 is passed through an aperture 37 in the shield.

From the foregoing description taken in 55 connection with the apparatus shown in Figs. 1 to 5 inclusive, it will be seen that either one of the antennae of the respective sets may be rendered operative at will, my improved antenna being employed as a 60 transmitter of electrical and light waves for transmitting a wireless signal from the wireless set or a private signal by the beam of light that can be intermittently interrupted by the switch 34.

In Fig. 6 of the drawings, I have shown 65 a form of ground plate which may be used in grounding the receiving and transmission sets, the ground plates being fastened to a metallic part of the structure in which my apparatus is installed.

In order that the throttle valve may be closed and the air brakes simultaneously applied, when my apparatus is employed on trains I employ an arrangement such as is shown in Figs. 7, 8 and 9. In Fig. 7 the 70 valve rod 38 of the throttle valve controlling the flow of steam from the steam dome of the boiler to the engine cylinders is formed of brass or other non-magnetic material and carries a core of iron or other magnetic material 39 adapted to be influenced by a solenoid magnet 40 supported by a bracket 41 secured to an appropriate part of the engine. The handle 42 of the engineer's controlling valve of the air brake system is 75 provided with a pin 43 disposed within a slot 44 formed in a link 45 pivotally connected as at 46 to the stem of an iron core 47 disposed within the influence of a solenoid magnet 48 secured to a suitable support 49, the latter being formed to provide for a shank 50 composed of brass or other non-magnetic material and connected to and supporting the core 47. The magnets 40 and 48 are connected in series in a circuit 80 51 including a source of electrical energy such for instance as a battery 52 and designed to be closed by means of a push button 53 or other form of switch carried by the box-like structure 1. Thus when the 100 engineer of a train receives a signal designating danger ahead, he may instantly close the throttle valve thereby cutting the flow of steam to the engine cylinders, and apply the air brakes, by pushing the button 53.

It will be noted that the slot 44 formed in the link 45 and receiving the pin 43 carried by the air brake controlling handle 42 is of such a length that the valve may be freely manipulated in the normal condition 105 of the apparatus.

While I have herein shown and described one preferred form of my invention by way of illustration, I desire to have it understood that I do not limit or confine myself to the 115 precise details of construction herein described and delineated, as modification and variation may be made within the scope of the claims and without departing from the spirit of the invention.

I claim:

1. In a signaling device, an antenna comprising a concave reflecting section, a metallic backing for said section capable of collecting magnetic waves, and an illuminating device within the focus of the said concave reflecting section.

2. In a signaling device, an antenna com-

prising a concave reflecting section, a concave metallic backing having its marginal edge bent over and secured to the marginal edge of said section, the said backing being capable of collecting magnetic waves, and an illuminating device in the focus of the said concave reflecting section.

In testimony whereof I affix my signature in presence of two witnesses.

GEORGE WILSON
